FIG. 1

FIG. 2

FIG. 3

FIG. 4

FIG. 5

FIG. 6

FIGURE 1 is a top plan view of a dispensing head for a pressurized can, showing my new design;

FIGURE 2 is a front perspective thereof;

FIGURE 3 is a bottom plan view thereof;

FIGURE 4 is an elevational view thereof taken from the right of FIGURE 2;

FIGURE 5 is a cross-sectional view taken through the center thereof; and

FIGURE 6 is a rear elevational view thereof.

The characteristic features of my design reside in a dispensing head having a flat top with serrations on the particular axis shown in combination with conical sides having the dispensing recess of the specific shape shown therein.

I claim:

The ornamental design for a dispensing head for a pressurized can, as shown and described.
